UNITED STATES PATENT OFFICE.

WILLIAM H. BRISTOL, OF WATERBURY, CONNECTICUT.

METHOD OF RECORDING SOUND.

1,380,864.

Specification of Letters Patent. Patented June 7, 1921.

Application filed January 13, 1920. Serial No. 351,146.

To all whom it may concern:

Be it known that I, WILLIAM H. BRISTOL, a citizen of the United States, and a resident of Waterbury, in the county of New Haven 5 and State of Connecticut, have invented certain new and useful Improvements in Methods of Recording Sound, of which the following is a specification.

The invention relates to a method of and 10 apparatus for effecting a record of a vocal or instrumental selection with suitable accompaniment. Heretofore, it has been the practice to collect the sound waves emanating both from the soloist and the accompanying 15 instrument or instruments by means of a horn or horns and, through the vibration of a diaphragm, to affect an acoustically actuated sensitive cutting member which is designed to engage a surface of plastic ma- 20 terial to make the original record from which in turn is made a suitable master in well-known manner. I have found, how- 25 ever, that in thus producing a record with accompaniment that the latter suffers in that it is difficult to faithfully reproduce the different instruments. Piano accompani- 30 ments have been especially difficult to re- produce satisfactorily.

The present invention has for its object to 35 effect a more natural record of the music of an accompanying orchestra, piano, organ or the like; and particularly to allow for the recording of a greater number of instruments than has been heretofore practical.

In carrying out the improved method, I 40 have found that with vocal selections perfect articulation is maintained, the recording being effected in the usual manner as trans- 45 formations impair the reproduction, and that the instrumental accompaniment is, furthermore, faithfully rendered and may be had at the desired intensity. It will be appreciated, where both the sound waves emanating from the instruments as well as 50 those from the soloist are to be collected by a horn or resonator apparatus common to both, as generally carried out, that the instruments must be located at a limited distance from one portion of the horn and that 55 an artist or artists must render the selection practically into the mouth of the said horn.

In accordance with the present invention, 60 the vocal or other selection is rendered substantially as heretofore by the soloist in close 65 proximity to the mouth of a horn, but the

instruments are located at an appreciable distance from their collecting instrumen- 70 tality and from the artist or artists, who may be, preferably, also acoustically insulated therefrom. Moreover, the sound emanating from the instruments is not received directly by the mouth of a horn; but the combined sound waves therefrom are to be received by an electrical transmitting instrument to af- 75 fect same, the impulses thereof amplified, and then directed to the recording apparatus. In this manner, no excessive strain is put upon the transmitter member which need only faintly transmit the sound waves, the 80 location being such that a not too strong ac- tion is produced thereon from the instru- 75 ments, the transmitter for this purpose being preferably located at an appreciable distance therefrom, for example from 10 feet to 35 feet away. This allows for the repro- 85 duction of the renditions of a full symphony orchestra, as comparatively weak impulses thus reproduced by the transmitter are properly amplified by a thermionic ampli- 90 fier of audio frequency, whereupon impulses of sufficient intensity are provided and are caused to affect the recording mechanism si- 95 multaneously with the impulses received through the horn from a song of a singer or from musical instruments to be accompanied. 85 A conductor may be so positioned as to view both the orchestra and the soloist; and the individual instruments composing the 90 orchestra are of course to be arranged at distances best suited to the reproduction, being 95 so located, also, with reference to the trans- 100 mitter as to provide for the proper intensity of the transmitted impulses. The entire recording may be conducted in a room suit- ably constructed and acoustically arranged for that purpose and in which there may be provided a partition or separating wall to acoustically insulate the soloist as well as the recording mechanism from the direct ef- 105 fect of the instruments, thereby individu- alizing the selection. Thus, the recording mechanism may be installed in a convenient location and preferably in manner that both the soloist and the orchestra shall be visible to the conductor.

The accompanying drawing illustrates, 105 diagrammatically, the general arrangement and apparatus employed in carrying out the novel method of effecting a record of a selec- 110 tion with accompaniment.

As shown, the recording may be effected in a room or a suitable inclosure 1 arranged to prevent the reflection of sound waves, the various instruments 2, constituting the orchestra or the like, being arranged in any suitable manner for example as at the back of the room while the position of the singer or soloist 3 is removed some distance therefrom and also acoustically insulated from 10 the said instruments by means of a wall or partition 4. The recording apparatus 5, may be of any of the well-known types and forms no particular feature of the present invention, and is to be located in proximity 15 to the soloist 3 so that the horn 6 of said apparatus may receive directly through its mouth the sound waves emanating from the soloist 3.

The horn 6 is provided, however, with an 20 inlet or second opening 7 near its inner end and through which sound waves, received in manner hereinafter set forth, are combined with those delivered into the mouth of the horn 6 to act simultaneously upon the recording portion of the recording apparatus

5. The sound waves emanating from the orchestra 2 are, therefore, not directly delivered into the horn 6, as has been the practice heretofore, but are collected by an 30 electrical transmitting device 8, of any well-known or special construction and the impulses set up thereby may be amplified by a suitable electrical amplifying apparatus 9 of audio frequency, such as a one or more stage 35 amplifier of the "Audion" type. From this amplifier, the impulses, properly magnified, are directed to a receiver member 10 communicating with the inlet 7, the receiver in turn delivering the sound waves through 40 said inlet 7 to the horn 6 and the diaphragm of the recording apparatus 5.

The conductor 11 may be located at any convenient point where he may view both the orchestra and soloist to suitably direct 45 both. It will be understood, of course, that the various orchestral instruments 2 will be arranged in positions best suited to the reproduction desired, the transmitter 9 being located at a distance therefrom to afford 50 the best results and provide the desired intensity, suitable regulation being thereby provided for.

I claim:—

1. The method of effecting upon a suitable record surface, a phonographic record of a 55 selection with accompaniment, which consists in individualizing the selection, separately collecting the accompaniment, amplifying same and simultaneously recording both upon the same record surface. 60

2. The method of effecting upon a suitable record surface, a phonographic record of a selection with accompaniment, which consists in individualizing the selection, separately collecting the accompaniment at an 65 appreciable distance from its origin, subjecting same to thermionic amplification of audio frequency solely, and simultaneously recording both upon the record surface.

3. The method of effecting upon a suitable 70 record surface a phonographic record of a selection with accompaniment, which consists in acoustically separating the selection from its accompaniment, rendering the former in immediate proximity of recording 75 mechanism, and collecting electrically the accompaniment.

4. The method of effecting upon a suitable record surface, a phonographic record of a selection with accompaniment, which consists in acoustically separating the selection from its accompaniment, rendering the former in immediate proximity to recording mechanism, collecting electrically the accompaniment, electrically transmitting and 80 thermionically amplifying same, and simultaneously recording both upon the same record surface. 85

5. The method of effecting upon a suitable record surface, a phonographic record of a 90 vocal selection with instrumental accompaniment, which consists in acoustically separating the vocal selection from its instrumental accompaniment, rendering the former in immediate proximity to recording 95 mechanism, collecting the accompaniment and electrically transmitting same and under thermionic amplification, and simultaneously recording the two upon the same record surface. 100

Signed at Waterbury in the county of New Haven and State of Connecticut this 10th day of January A. D. 1920.

WILLIAM H. BRISTOL.
